COMBINED ROAD ROLLER AND GRADER

Edgar V. Biles, San Antonio, Tex., assignor to
Carl H. Graham, San Antonio, Tex.

Application April 29, 1935, Serial No. 18,897

19 Claims.

(Cl. 94—50)

The invention relates to a road working machine and more especially to a combined road roller and grader.

The primary object of the invention is the provision of a machine of this character, wherein the same is self-propelled when active for the grading or rolling of a roadbed or when inactive for these purposes and under transportation from one locality to another, the machine in its entirety being of novel construction and requiring minimum manual labor in converting the said machine for the purposes specified.

Another object of the invention is the provision of a machine of this character, wherein the driving of the road rollers and the traction wheels is had from a power source, such as a motor built into the machine and the driven connection being differential action so that the machine can be readily turned and the road rollers can be readily altered as to weight, according to the requirements of road conditions.

A further object of the invention is the provision of a machine of this character, wherein the rubber or other tired traction wheels can be brought into position for transportation purposes when the road rollers have been elevated and inactive for road working, for convenience in the travel of the machine from one locality to another with rapidity, so that delay will be avoided as otherwise would occur should it be required to transport the machine other than by its own power.

A still further object of the invention is the provision of a machine of this character, wherein the same is arranged and equipped for satisfying road working under varying conditions, as the machine will function for the grading of the road and the rolling of its bed and is susceptible of control by a single operator.

A still further object of the invention is the provision of a machine of this character which is comparatively simple in its make-up, thoroughly reliable and efficient in its purposes, strong, durable, and inexpensive to manufacture.

With these and other objects in view, the invention consists in the features of construction, combination and arrangement of parts as will be hereinafter more fully described in detail, illustrated in the accompanying drawings, which disclose the preferred embodiment of the invention, and pointed out in the claims hereunto appended.

In the accompanying drawings:

Figure 1 is a top plan view of the machine constructed in accordance with the invention.

Figure 2 is a side elevation thereof, the ma-

chine being converted for transportation purposes, with the grading means and the road rollers inactive.

Figure 3 is a view similar to Figure 2 showing the machine converted for activity of the grading means and road rollers and modified to operate as a three roller machine.

Figure 4 is a sectional view on the line 4—4 of Figure 3 looking in the direction of the arrows and having the rear rollers in the position shown in Figure 2.

Figure 5 is a fragmentary sectional view on the line 5—5 of Figure 2 looking in the direction of the arrows.

Figure 6 is a fragmentary perspective view on an enlarged scale showing the rear end portion of the chassis and adjuncts.

Figure 7 is a fragmentary sectional view on the line 7—7 of Figure 1.

Figure 8 is a sectional view on the line 8—8 of Figure 7.

Figure 9 is a fragmentary sectional view on the line 9—9 of Figure 4 looking in the direction of the arrows.

Figure 10 is a transverse sectional view through the braking mechanism.

Figure 11 is a sectional view on the line 11—11 of Figure 10.

Figure 12 is a fragmentary top plan view of the braking mechanism at one side of the machine.

Figure 13 is a sectional view on the line 13—13 of Figure 14 looking in the direction of the arrows.

Figure 14 is a sectional view on the line 14—14 of Figure 13 looking in the direction of the arrows.

Figure 15 is a sectional view on the line 15—15 of Figure 14 looking in the direction of the arrows.

Figure 16 is a vertical transverse sectional view through the modified form of rear roller of the machine.

Figure 17 is an elevation looking toward the tread thereof.

Figure 18 is a side elevation.

Figure 19 is a fragmentary enlarged sectional view thereof at the point of a fastener.

Figure 20 is a front elevation of the front wheel of the machine showing a modification constituting a front roller.

Figure 21 is a fragmentary vertical sectional view showing a side elevation of the structure in Figure 20.

Figure 22 is a vertical transverse sectional view thereof.

Figure 23 is an elevation looking toward the inner side of one section of the roller.

Figure 24 is a side view thereof.

Similar reference characters indicate corresponding parts throughout the several views in the drawings.

Referring to the drawings in detail, the machine comprises a main frame or chassis A including the side beams or sills 10, these being forwardly tapered at their front portions, while located at the forward end of the chassis or frame is the single front steering wheel 11, journaled in a turning fork 12 having a gear wheel sector 13 at its upper end meshing with a pinion 14 operated by a steering shaft 15 including the universal knuckles 16 and carrying a hand wheel 17 which is located conveniently for reach by an operator when occupying the seat 18. This seat 18 is carried upon a fuel supply tank 19 suitably built in the chassis or frame. The steering shaft 15 is suitably supported upon a hood 20 increasing the motor (not shown) of the internal combustion engine type. The motor has a suitable mount within the chassis or frame A and the hood 20 is carried in a conventional manner.

Located near the rear end of the chassis or frame A, transversely thereof and suitably supported, is a driven shaft or axle 21 on which are arranged the companion road rollers 22, in pair, and this shaft 21 at one end is reduced, at 23, for the loose fitting of a bushing 24 thereon keyed to the bushing 24 and to the shaft 21 at the outer sides of the rollers 22 are the hubs 25 of sprocket wheels 26 having trained thereover the endless sprocket chains 27, these being trained over sprocket gears 28 operated and controlled through a conventional type of gear shift automotive transmission, clutch and differential between the same and the motor, the gear shift lever being indicated at 29 and the clutch pedal at 30, respectively. Cooperating with these gears 28 is a suitable braking mechanism 31 operated from the hand controls 32. Thus it will be seen that power from the motor will be transferred to the shaft 21.

At the rear end of the chassis or frame A are arranged laterally swinging hangers 33 carried by pivots 34 in suitable bearings 35 formed in the side beams or sills 10, these hangers 33 being inclined, and at their outer ends support singular or dual pneumatic or solid rubber or other tired traction wheels 36, the angular disposition of the hangers 33 being to permit the said wheels 36 to be raised to the proper extent when swung out of contact with the ground or a road surface, for a purpose presently described. Normally the wheels 36 contact with the ground for mobility of the machine, especially for convenient transportation thereof under its own power, as herein-after set forth.

The side sills or beams 10 of the chassis or frame A have formed in their outer faces the angularly disposed channels or grooves 37, these being adapted to accommodate the hangers 33 when the wheels 36 contact with the ground or road surface when the said wheels are burdened with the weight of the machine at the rear end of its chassis or frame. In other words, the hangers 33, when the wheels 36 are in the position as just mentioned, will interfit the chassis or frame A and thus transfer the weight of the load directly to the wheels 36.

Carried by the sills or beams 10 are hand controlled latching bolts 38, these being engageable in keepers 39 on the hangers 33, and such bolts function to lock the said hangers in the grooves 37 or channels 37 to sustain the wheels 36 in sup-

porting position when contacting with the ground or road surface.

On the hubs of the wheels 36 at their inner sides are gears 40, these being adapted for meshing engagement with idle gears 41 suitably journaled on the chassis or frame 10 and at all times in mesh with gears 42 fixed to the bushing 24 and shaft 21, respectively, the gears 42 being held secure by nuts 43. Thus it will be seen that when the wheels 36 are thrown to engage the ground or road surface the gears 40 will enmesh with the gears 41, these being in meshing engagement with the gears 42 power can be transmitted from the motor to the said wheels 36 for the mobility of the machine.

Formed in the hubs 25 of the sprocket wheels 26 are latching notches or recesses 44, while carried at the outer sides of the rollers 22 are latching bolts 45, these being slidable through guides 46 and having their stems 47 carrying coiled springs 48 which act upon the bolts 45 to throw the same to locking position, while pivoted to the upper ends of the stems 47 are cam-acting releasing levers 49 which retract the bolts 45 when swung in one direction and when moved in the reverse direction permit the springs 48 to become active for the throwing of the bolts to locking position. The rollers 22, when elevated by the traction wheels 36 upon the ground or roadbed, will be released by the bolts 47, so that the same will not rotate under power, but when the rollers 22 are in contact with the ground or roadbed, the bolts 45 will have been thrown to locking position with the hubs 25, so that such rollers will be positively driven under power from the motor of the machine and when the rollers 22 are in contact with the ground or roadbed, the wheels 36 will have been raised out of contact with said ground or roadbed.

Arranged forwardly of the rollers 22 is a scraping or grading blade 50, the same being swingingly adjusted and raised and lowered in any desirable manner and its purpose is to scrape or grade a roadbed or ground, this operation being effective either when the traction wheels 36 are raised out of contact with the ground or roadbed and the rollers 22 in contact therewith, or when the wheels 36 are in contact with the ground.

Provided in the outer sides of the rollers 22 are suitable openings 51 covered by removable closure plates 52 and the purpose of these openings is to vary the ballast of the rollers to increase or decrease the weight thereof according to the requirements of road conditions during the rolling operation of the machine.

Assuming that the rollers 22 are in contact with the ground or road surface for action thereon and it is desired to execute road work at a remote location, it becomes necessary to use chocks or tapered skids 53 which are placed at rest upon the ground or roadbed rearwardly or forwardly of the rollers 22 so that on the movement of the machine the said rollers 22 will ride onto these chocks or tapered skids 53, thereby elevating the rear end of the chassis at the required height to bring the wheels 36 into traction position, the said wheels being locked in this position by the latching bolts 38 which engage the keepers 39 on the hangers 33, and on the advancement of the machine under its own power, the rollers 22 will be maintained passive and the same, with the grader 50, transported to the desired locality. On arriving at the working locality the locking bolts 45 are engaged with the notches or recesses 44. Otherwise, traction of

- wheels 36 will be lost when rollers 22 make contact with skid blocks 53. The power to raise wheels 36 clear of the ground must then be transmitted through the rollers 22 and the chocks 5 or tapered skids 53 are placed in position so that the rollers will travel onto the same and thus holding the chassis elevated at the rear portion to permit the wheels 36 to be thrown out of contact or traction position with respect to the ground or roadbed, as is clearly shown in Figure 3 of the drawings, whereupon the machine is ready for road working, the traction position of the wheels being clearly shown in Figure 2 of the drawings.
- 15 The differential connections between the motor, rollers 22 and the wheels 36 will permit the machine to turn, as will be apparent. It is, of course, understood that when the rollers are in contacting relation with the ground or roadbed 20 the bolts 45 will lock the same with the hubs 25 of the sprocket wheels 26, so that power direct from the motor will be transmitted to said rollers.
- At the rear end of the chassis or frame A is a support 54 for a water tank 55 having the discharge spray device 56 for directing water onto the outer contacting surfaces of the rollers 22 to prevent the sticking of road building materials thereto during the rolling operation of the machine.
- 30 With reference to Figures 3, 4, 16 to 24, inclusive, there is disclosed a modified arrangement for roller action of the machine, and wherein the front steering wheel 11 has attached thereto two half cylinder sections 57, these being mates to encircle the said wheel 11 and are separably joined with each other through inner angle cleats 58 fixedly attached at the abutting ends of said sections 57 and receive fasteners 59. These sections are formed with radial spokes 60 which are detachably bolted at 61 to the central portion of the wheel 11 about the hub thereof and in this fashion the wheel 11 is converted into a front road roller, the turning fork 62 being sized for accommodating the front road roller.
- 45 Each roller 22 at the rear of the machine has fitted therewith detachable shoes 63, these in group mate each other and are disposed peripherally about said roller, they having countersunk holes 64 for screws 65 to engage in countersunk holes 66 in the roller 22 and in this fashion the shoes are worn by the roller and such shoes are arranged at the outermost edge side of such roller so that there will be a gap between the shoes worn by both rollers 22 of a less width than the 55 width of the front road roller and thus the machine is converted into a three roller machine with the rear rollers tracking at opposite sides of the front roller and the rear shoes operating with the rollers 22 in view of the spacing of the shoes 60 will eliminate the print of the front road roller on the surface of the road during the working of the machine.
- When the shoes 63 are detached the fasteners 65 are counterseated in the holes 66 in each roller so that the outer surface of the latter will be 65 smooth and the countersunk holes 66 therein closed. When the fasteners 65 are engaged in the shoes 64 the outer surface of the shoes will 70 be smooth.
- It is required with road building equipment to employ a tandem roller machine and a three roller machine, the tandem roller machine being usable for finishing work while the three roller machine 75 is for base work. Therefore, the machine herein

described is usable as a tandem roller or three roller machine.

When the shoes 63 are worn by the rear rollers 22 the said shoes only make contact with the ground or road surface and in the use of the three roller machine a more uniform compaction of the road surface may be secured than by the use of the tandem roller machine.

What is claimed is:

1. In a machine of the character described, a frame having road roller equipment, a power unit carried by the frame and having driven connections with said roller equipment, rear wheels swingingly connected with the frame and movable to and away from a road surface and when engaged with said road surface elevating the roller equipment from contact therewith, and driven connections between the power unit and said wheels.
2. In a machine of the character described, a frame having road roller equipment, a power unit carried by the frame and having driven connections with said roller equipment, rear wheels swingingly connected with the frame and movable to and away from a road surface and when engaged with said road surface elevating the roller equipment from contact therewith, driven connections between the power unit and said wheels, and means for releasing the roller equipment from connections with the power unit when said roller equipment is elevated.
3. In a machine of the character described, a frame having road roller equipment, a power unit carried by the frame and having driven connections with said roller equipment, rear wheels swingingly connected with the frame and movable to and away from a road surface and when engaged with said road surface elevating the roller equipment from contact therewith, driven connections between the power unit and said wheels, means for releasing the roller equipment from connections with the power unit when said roller equipment is elevated, a front steering wheel mounted in the frame, and hand operated steering mechanism for controlling said steering wheel.
4. In a machine of the character described, a frame having road roller equipment, a power unit carried by the frame and having driven connections with said roller equipment, rear wheels swingingly connected with the frame and movable to and away from a road surface and when engaged with said road surface elevating the roller equipment from contact therewith, driven connections between the power unit and said wheels, means for releasing the roller equipment from connections with the power unit when said roller equipment is elevated, a front steering wheel mounted in the frame, hand operated steering mechanism for controlling said steering wheel, and a road grader arranged in the frame fore of said roller equipment.
5. In a machine of the character described, a frame having road roller equipment, a power unit carried by the frame and having driven connections with said roller equipment, rear wheels swingingly connected with the frame and movable to and away from a road surface and when engaged with said road surface elevating the roller equipment from contact therewith, driven connections between the power unit and said wheels, means for releasing the roller equipment from connections with the power unit when said roller equipment is elevated, a front steering wheel

mounted in the frame, hand operated steering mechanism for controlling said steering wheel, a road grader arranged in the frame fore of said roller equipment, and means releasably latching the rear wheels in traction position.

6. In a machine of the character described, a frame having road roller equipment, a power unit carried by the frame and having driven connections with said roller equipment, rear wheels swingingly connected with the frame and movable to and away from a road surface and when engaged with said road surface elevating the roller equipment from contact therewith, driven connections between the power unit and said wheels, means for releasing the roller from connections with the power unit when said roller equipment is elevated, a front steering wheel mounted in the frame, hand operated steering mechanism for controlling said steering wheel, a road grader arranged in the frame fore of said roller equipment, means releasably latching the rear wheels in traction position, and a differential included in the connections between the power unit and said wheels.

7. In a machine of the character described, a frame having road roller equipment, a power unit carried by the frame and having driven connections with said roller equipment, rear wheels swingingly connected with the frame and movable to and away from a road surface and when engaged with said road surface elevating the roller equipment from contact therewith, driven connections between the power unit and said wheels, means for releasing the roller from connections with the power unit when said roller equipment is elevated, a front steering wheel mounted in the frame, hand operated steering mechanism for controlling said steering wheel, a road grader arranged in the frame fore of said roller equipment, means releasably latching the rear wheels in traction position, and a differential included in the connections between the power unit and said wheels, the said roller equipment being formed in several sections.

8. In a machine of the character described, a frame having road roller equipment, a power unit carried by the frame and having driven connections with said roller equipment, rear wheels swingingly connected with the frame and movable to and away from a road surface and when engaged with said road surface elevating the roller equipment from contact therewith, driven connections between the power unit and said wheels, means for releasing the roller from connections with the power unit when said roller equipment is elevated, a front steering wheel mounted in the frame, hand operated steering mechanism for controlling said steering wheel, a road grader arranged in the frame fore of said roller equipment, means releasably latching the rear wheels in traction position, a differential included in the connections between the power unit and said wheels, the said roller equipment being formed in several sections, and hand controlled independent braking mechanisms cooperative with said connections between the wheels, roller equipment and the power unit.

9. In a machine of the character described, a frame, road roller means journalled therein and presenting a substantially continuous rolling surface from one end to the other thereof, removable shoes fitted to said road roller means and forming axially spaced circumferential bands thereabout to cause said road roller means

to present a plurality of axially spaced rolling surfaces, whereby road roller means may be employed selectively as a single continuous rolling means or as a plurality of axially spaced rolling means.

10. In a machine of the character described, a frame, rear road roller means journalled therein and presenting a substantially continuous rolling surface from one end to the other thereof, a front steering wheel on said frame, removable shoes fitted with the rear road roller means and arranged in axially spaced circumferential bands to cause said rear road roller means to present a plurality of axially spaced rolling surfaces, roller sections removably fitted with the front wheel, the so-formed rolling surfaces on the rear roller means tracking the opposite sides of the roller sections carried by the front wheel, a power unit carried by the frame and having driven connections with the rear roller means, rear wheels swingingly connected with the frame and movable to and away from a road surface, and when engaged with said road surface elevating the rear roller means from contact therewith, and driven connections between the power unit and said wheels.

11. In a machine of the character described, a frame, rear road roller means journalled therein and presenting a substantially continuous rolling surface from one end to the other thereof, a front steering wheel on said frame, removable shoes fitted with the rear road roller means and arranged in axially spaced circumferential bands to cause said rear road roller means to present a plurality of axially spaced rolling surfaces, roller sections removably fitted with the front wheel, the so-formed rolling surfaces on the rear roller means tracking the opposite sides of the roller sections carried by the front wheel, a power unit carried by the frame, and having driven connections with the rear roller means, rear wheels swingingly connected with the frame and movable to and away from a road surface, and when engaged with said road surface elevating the rear roller means from contact therewith, and driven connections between the power unit and said wheels.

12. In a machine of the character described, a frame, rear road roller means journalled therein, and presenting a substantially continuous rolling surface from one end to the other thereof, a front steering wheel on said frame, removable shoes fitted with the rear road roller means and arranged in axially spaced circumferential bands to cause said rear road roller means to present a plurality of axially spaced rolling surfaces, roller sections removably fitted with the front wheel, the so-formed rolling surface on the rear roller means tracking the opposite sides of the roller sections carried by the front wheel, a power unit carried by the frame and having driven connections with the rear roller means, rear wheels swingingly connected with the frame and movable to and away from a road surface, and when engaged with said road surface elevating the rear roller means from contact therewith, means for releasing the rear roller means from connections with the power unit when said rear roller means is elevated.

13. In a machine of the character described, a frame having road roller equipment, a power unit

carried by the frame, rear wheels movably connected with the frame and movable to and away from a road surface and when engaged with said road surface elevating the roller equipment from contact therewith, and means operatively connecting said power unit selectively to said wheels and to said roller equipment.

5 14. In a machine of the character described, a frame, a roller journalled therein, an arm swingingly mounted on said frame on a non-vertical axis, a wheel mounted on said arm at a position remote from said axis and adapted when said arm is swung downwardly to support said frame and roller, and means for latching said arm in its

15 down position.

15 15. In a machine of the character described, a frame, a roller journalled therein, arms swingingly mounted on said frame on non-vertical axes adjacent the opposite ends of said roller, 20 wheels mounted on said arms, respectively, and so positioned thereon that when said arms are in their down position said wheels will support said frame and roller, and means for latching said arms in their down position.

20 16. In the machine of the character described, a frame, a roller journalled therein, arms swingingly mounted on said frame on non-vertical axes adjacent the opposite ends of said roller, wheels mounted on said arms, respectively, and so positioned thereon that when said arms are in their

25 30

down position said wheels will support said frame and roller, means for latching said arms in their down position, said arms and wheels being so arranged with respect to said roller that when said arms are swung to their up position said wheels 5 will overlie the path of said roller, and means for latching said arms in their up position.

17. In a machine of the character described, a frame, a road roller journalled in said frame, wheels swingingly connected with the frame and 10 movable to and away from a road surface, said wheels when not in contact with a road surface being movable to a position overlying the path of said roller.

18. In a machine of the character described, a frame, a road roller journalled in said frame, wheels connected with the frame and movable to and away from a road surface, said wheels when not in contact with a road surface being movable to a position overlying the path of said roller. 15

19. In a machine of the character described, a frame, a road roller journalled in said frame, wheels swingingly connected with the frame for swinging movement downwardly and forwardly into contact with a road surface and upwardly 20 and rearwardly away from such road surface, said wheels when in their upward and rearward position occupying a position overlying the path of said roller. 25

EDGAR V. BILES. 30
